GUNNERY TRAINING APPARATUS

Fred Waller, Huntington, N. Y., Willis Robert Dresser, Long Hill, Conn., and Robert R. Swain, Huntington, N. Y., assignors to The Vitarama Corporation, Long Island City, N. Y., a corporation of New York

Application May 20, 1944, Serial No. 536,579

17 Claims. (Cl. 35—25)

1

This invention relates to gunnery training apparatus of the type which has come to be identified by the services using it as the "Waller trainer," the same being disclosed in the copending application of Fred Waller, Willis Robert Dresser and Henry Martyn Baker, Serial No. 415,374, filed October 17, 1941 now Patent No. 2,406,574, and assigned to the assignee of the present application. This trainer uses picture film to project target images upon a screen and uses control film to register the gunner's accuracy of aim and to produce various other desired effects. The present apparatus is designed to prepare or "edit" the control film used in the trainer described in said application and is especially designed to edit the improved control film described and claimed in the copending application of Fred Waller, Willis Robert Dresser, Robert R. Swain, and Raymond William Wengel, Serial No. 536,578, filed May 20, 1944, and assigned to the assignee of the present application.

The improved control film disclosed in the last-mentioned Waller et al. application is provided with parallel light aperture zones across the film in each frame in which control indicia are desired. The term "frame" is not used here in the strict sense in which it is used in relation to picture film but in a rather loose sense to designate the length of film which is halted at various associated mechanisms for each frame of picture film which is synchronously exposed at each pull-down cycle. In order to furnish a ready reference, the present invention provides for the placing of a transverse registry line at a given point relative to the indicia zones by which the film may be positioned or adjusted in the projecting apparatus.

Some of the indicia may fall above and some below the transverse index line for any given "frame" on the band.

The indicia in the various transverse zones provide for different functions or effects. Thus there is a zone for azimuth or horizontal location of the aim spot relative to some fixed reference line. In the present case the reference line is a vertical median line on the projection screen, which might also be described as the median line of a picture frame if it is remembered that instead of a single projector for one band or frame a plurality of projectors are preferably used to project a composite mosaic picture on a curved concave screen. Azimuth is measured to the right and to the left of the center, hence there will be two horizontal zones for azimuth.

2

There will also be a transverse zone allotted for elevation or the vertical location of the aim spot relative to some given horizontal reference line on the projection screen. In the present case the reference line is taken as the top edge of the screen, which again may be spoken of as the top edge of the picture frame if it is remembered that the resultant of the several mosaic-forming frames is meant.

10 The azimuth and elevation indicia are dealt with together inasmuch as they are employed conjointly to fix the aim spot. By a conversion system they are all referred to a single index or base line at or parallel to the edge of the film, preferably an unmarked base line just within the left line of sprocket holes as the film will be shown herein.

In like manner as explained in the first above-mentioned Waller et al application, there are a number of other zones for other functions or effects, as for example, a zone for lag or time of projectile flight to the target, and a zone for certain positional control functions for automatic gun or spot control, aim correction, or trajectory control, such as "up," "down," "right," "left," "zero," "multiplier," "register letter," "spare," and the like.

20 The equipment to be described herein is intended only to place indicia in the azimuth, elevation, and lag zones and to place a horizontal registry line on the film; however, a band will be described with all zones reserved which have been mentioned.

25 With this general explanation of the present intended field of the invention and with the observation that the invention aims to provide suitable apparatus for photographically altering a sensitized control band to place the desired indicia and to provide a convenient method of obtaining the desired effects, it will be helpful to proceed immediately to the examination of one form of apparatus which has been effectively used for the intended purpose. The apparatus may be designated as an editing machine or editor. The above-mentioned and other objects of the invention will be apparent from the following description of this exemplary embodiment, reference being made to the accompanying drawings thereof, wherein:

30 Figure 1 is a face view of a short length of control film or band with indicia thereon, formed according to the present invention;

35 Figure 2 is a face view of a short length of control film according to the first Waller et al.

application to show an aim spot and its locating coordinates;

Figure 3 is a face view of a short length of control film according to the second Waller et al. application with a revised representation of an aim spot at the same coordinate location as in Figure 2;

Figure 4 is a view like Figure 2 but showing a central aim spot location;

Figure 5 is a view like Figure 3 of the new locational representation of the aim spot of Figure 4;

Figure 6 is a view like Figures 2 and 4 but showing still another aim spot location;

Figure 7 is a view like Figures 3 and 5 of the new locational representation of the aim spot of Figure 6;

Figure 8 is a face view of a series of masks used to form the azimuth apertures;

Figure 9 is a face view of a series of masks used to form the elevation apertures;

Figure 10 is a schematic plan view of the editing apparatus;

Figure 11 is a partial elevation of the screen shown in Figure 10 showing how the target distance is determined;

Figure 12 is an enlarged elevation of an aiming device or dummy gun shown in Figure 10;

Figure 13 is a vertical transverse broken section through the photographic editing device, the section being taken on the line 13-13 of Figure 15;

Figure 14 is an axial vertical section taken on the line 14-14 of Figure 15;

Figure 15 is a horizontal section taken on the line 15-15 of Figure 14;

Figure 16 is an enlarged partial section taken on the line 16-16 of Figure 15;

Figure 17 is a horizontal partial section taken on the line 17-17 of Figure 16;

Figure 18 is an enlarged section of a part of the apparatus shown in Figure 13, the viewing position being reversed to look from back to front instead of from front to back as in Figure 13; and

Figure 19 is an enlarged vertical section taken on the line 19-19 of Figure 18.

The product will be described first to show what the method and apparatus are intended to achieve. In Figure 1 a short length of control band 30 is shown with spaces set apart to indicate zones reserved for various indicia. The lines of separation between zones and the zone legends do not appear on the actual film but are used here for pictorial aid. The film moves downward in service as indicated by the arrow at the bottom, and the left edge 31 is accurately guided at the film gate, both in the editing apparatus during preparation and in the trainer during projection. The line 32 parallel to the left edge just inside the line of sprocket holes 33 is the important vertical index or base line which has already been referred to. The reserved transverse zones all lie between the vertical base line 32 and a boundary line 34 just inside the opposite line of sprocket holes. The lines 32 and 34 do not appear on the actual film.

The horizontal index or registry lines 37 do appear on the control film. They are placed there by the editing apparatus in a manner to be described. The space between alternate lines roughly constitutes one frame in the present scheme but other lengths may constitute a frame. As will be explained, the reason for having practically a double-length frame in the present case is that the physical space requirements of de-

pendable apparatus make a long frame space and substantial interspacing desirable and since it may be desired to follow two different targets at the same time on the same control band, the indicia for one may be in part interspersed with those of the other. The length of gate frames for the targets is shown in Figure 1. These horizontal index lines need not be photographed on the control band at every unit of length but only at places where they are desired and that is usually where the target is to be followed, whether or not any aim indicia thereof appear in the reserved areas.

For one target, designated as target No. 1, there is a zone 40 for time of flight, a zone 41 for azimuth right, a zone 42 for elevation, a zone 43 for azimuth left, and a zone 44 for trajectory control. The last zone 44 is shown as comprising the sub-zones 44a for spare or reserve, 44b for up, 44c for down, 44d for right, 44e for left, 44f for zero or cancel and return to zero, 44g for multiplier or repeat of any of the other operations under trajectory control, and 44h for a register letter or number to designate the target, frame or attack being depicted. The time of flight zone employs one photocell in projection; the three zones azimuth right, elevation, and azimuth left, together employ one photocell; and the trajectory control zone employs one photocell for each sub-zone or separate function.

The same control band is here used for following two targets and the indicia zones for the second target, No. 2, are designated by the same reference numerals as the first but with a line prime (') added. The gate frame lengths for the two targets overlap each other in order to space apart the zones for each target and provide more length for the physical apparatus needed for projection. Different gate and projection mechanism may be used for each target so this arrangement presents few objections and a number of advantages. Or the same projection mechanism, acting alternately for the two targets, may be used.

By analogous arrangement more than two targets may be provided for if desired. Using separate projection machines operating with different prints of this control band or stopping at different longitudinally displaced positions for different targets, the pull-down length when the two-target film illustrated is used will be that indicated on the left margin brackets in Figure 1 as "gate frame Target No. 1 (or No. 2)."

In Figures 2 to 7 short lengths of actual film (for one target only) are shown, Figures 2, 4 and 6 being the former type film where locational coordinates serve as actual representation of a single aim spot aperture, and Figures 3, 5 and 7 being the new type film where the locational coordinates are all referred to a single vertical base line and laid out in parallel horizontal transverse zones as shown in Figure 1. Only the aim spot locational apertures are represented, the aperture for time of flight or lag and the various apertures for trajectory control 44 being merely openings of any required size and shape (and location in the case of lag) necessary to pass a beam of light adequate to energize a photoelectric cell and hence omitted.

In Figure 2 the aim spot 50 is shown to the left of the center line 51. Assuming a frame to be 400 azimuth units wide and 400 elevation units long, the spot 50 is located at 100 units from a left base or index line 52, 100 units from a top index line 53, and 100 units from the center line

51. Its coordinates may then be abbreviated as H_{100}, V_{100} from the left and top index lines and as HL_{100}, VL_{100} from the middle and top lines. In Figure 3, where the two horizontal zones 41 and 43 for azimuth are 200 units in length and the zone 42 for elevation is 400 units in length and measured from the common vertical index line 32 at the left, the same spot, shown at 50 in Figure 2, is represented by the aperture 50a in the "azimuth left" zone 43, together with the aperture 50b in the "elevation" zone 42. The spot being located to the left of the center line in Figure 2, there is no aperture in the "azimuth right" zone 41 of Figure 3. The apertures 50a and 50b are each formed in two parts for clarity of definition and other reasons which are explained in the first Waller et al. application and which will be explained together with additional reasons herein.

In Figures 4 and 5 another point 55 at H_{200}, V_{200} is represented. It falls on the center line so may be designated as HL_0, HR_0, V_{200} . In Figure 5 it is jointly represented by the apertures 55a in the "azimuth right" zone 41, 55b in the "elevation" zone 42, and 55c in the "azimuth left" zone 43. The apertures 55a and 55c are half-size and near the left or zero index line, this being the representation of zero in the present system.

In Figures 6 and 7 a third aim spot 60 is depicted. Its location is H_{300}, V_{300} or HR_{100}, V_{300} and in Figure 7 it is represented jointly by the aperture 60a in the "azimuth right" zone 41 and 60b in the "elevation" zone 42.

In forming the apertures photographically by the apparatus to be described there is provision for making some apertures larger than others to provide more latitude of aim as the target gets nearer and intersects a wider cone of fire. This is indicated by the masks shown in Figures 8 and 9 for forming the apertures. Figure 8 represents the azimuth apertures, either right or left of center, and Figure 9 represents the corresponding elevation apertures. Say there are twelve masks, eleven with apertures and one with an obscuring plate, the first H_1 or V_1 will be that for greatest accuracy when the target is at the limit of the firing range and will be approximately the same size of aperture as that in the slide mask of the projection apparatus or trainer. The others H_2 to H_{11} , V_2 to V_{11} have apertures of increasing size until H_9, V_9 is reached. Here the two aperture elements merge into one which represents the maximum latitude of aim, and H_9, V_9 and H_{10}, V_{10} and H_{11}, V_{11} are merely rectangles, preferably of increasing length. Moreover, the "elevation" apertures no longer need to be inclined to compensate for film shrinkage (see the second-mentioned Waller et al. application), hence are made with vertical sides like the "azimuth" apertures.

Having noted the effects to be obtained, the apparatus and method for obtaining the desired results may be described. Figure 10 shows the editing apparatus as a whole. Most of the remaining figures are directed to the aperture forming device or camera.

A projector 65 directs target images from picture film upon a screen S. Only one projector is shown but in practice a plurality, five commonly, are used. There will be the same number and arrangement as in the gunnery trainer and both will be the same as the number and arrangement of cameras which photographed the target. The screen is preferably spherical with the concave side toward the projector. The projector

is operated by a motor M1 which will either run the film continuously or expose it frame by frame as a series of stills, changeable upon the supervisor's demand. The supervisor operates from a control panel 66, only a few of the details of which need be shown.

The image is followed by a pointer 67 which has the same position relative to the screen and focal axis as the corresponding dummy gun in the trainer. There will be as many pointers as there are dummy guns and because of their identical corresponding arrangement they automatically take care of parallax, i. e. the lateral displacement of the gunner's sight from the focal axis. Only one pointer is shown. The pointer is connected by cables 68, 69, 70 and 71 to a number of slides 72, 73 and 74 which fix the aim spot, the cables 68 and 69 actuating one slide operator and the cables 70 and 71 actuating another slide operator. The slides 72, 73 and 74 are the elevation and azimuth right and azimuth left locators respectively. In Figure 10 the two azimuth slides 73, 74 are placed one below the other so that only one appears.

A hand operator or dial 76 through a pair of cables 77, 78 actuates a lag or time of flight slide 79.

All of these slides are associated with a camera or editor 80 which forms the necessary control apertures or indicia in the sensitized control band.

The projector 65 and the editor 80 are driven by motors M1 (already referred to) and M2 respectively which are connected through a differential gear 81. The projector is provided with a counter 82, the editor with a counter 83, and the differential with a counter 84, all counters preferably being located at the supervisor's control panel 66. Normally the projector and editor run in synchronism and their counters register the same number of picture and control frames from the start of the films; but they may be operated to throw them out of phase by any desired number of frames and the differential counter indicates the number of frames of this displacement, plus or minus. When the differential counter reads zero the camera and editor are abreast again. The displacement is provided to take account of time of flight or lag whereby when the picture and control bands are run abreast in the trainer there will be an immediate hit indication if the gunner has led the target sufficiently.

Figure 12 shows how the pointer is mounted to operate the pairs of cables 68 and 69 for elevation and 70 and 71 for azimuth. The arrangement is similar to that of the dummy gun. The pointer 67 in the form of a telescope with vertical and horizontal crosshairs, is mounted on a horizontal shaft or axis 87 and the cables 68 and 69 for elevation are secured to a sector or pulley 88 fast on the shaft. The shaft 87 is mounted on a head 89 which is secured to a tubular vertical shaft 90 turnably mounted in a tubular pedestal 91. The lower end of the shaft 90 carries a sector or pulley 92 to which the cables 70 and 71 for azimuth are attached. The cables 68 and 69 are disposed substantially at the axis of the vertical shaft 90, hence are practically unaffected by the turning of this shaft.

Referring to Figure 11, when the image of a target T, such as an airplane, is projected on the screen S by a given frame of the picture film its best observed dimension is measured, as by calipers 93. Angularity is taken into account and the distance of the target computed by reference

to known dimensions of the particular airplane shown. Speed of travel of the target can be determined by its travel over a given number of frames of film, the speed of the picture camera being known. Of these and other data, such as projectile flight characteristics, gravity, windage, etc., there is made a log, frame by frame, for every sequence where a target is within firing range. Having this log of pertinent data the control film may be edited, frame by frame, as the picture film is re-run and the target is followed by the pointer.

At the left of Figure 13 there is shown the mechanism at the editor which is actuated by the cables 68, 69, 70, 71 when the pointer is operated. It comprises levers 95 and 96 mounted on a shaft 97 carried by a bracket 98 secured to the side of the editor. Since the front lever tends to hide the parts behind it, reference should also be made to Figure 15 which shows these parts in plan. The lower ends of the levers 95 and 96 are formed as sectors to which the pairs of cables 68 and 69 and 70 and 71 are respectively attached.

To the front lever 95, which is for azimuth, there are attached on opposite sides of the pivot shaft 97 two connecting rods 99 and 100 which are pivoted to azimuth slides 101 and 102. The slides therefore move simultaneously but in opposite directions. The upper 101, as used, represents distance to the right of the center line; and the lower 102 represents distance to the left of the center line.

To the second lever 96, which is for elevation, on one side of the pivot shaft 97 there is attached a connecting rod 105, which at its other end is pivoted to an elevation slide 106. The parts from the pointer to the slides are so proportioned that the elevation slide 106 has a length of movement only half as great as that of the azimuth slides. This provides for one azimuth slide aperture to traverse the width of the film while the other is off the film to the left and vice versa, each azimuth slide thus having a total range of movement twice as wide as the horizontal zone on the control band while the elevation slide traverses only the width of the film.

To the sector at the lower end of a third lever 108 the pair of cables 77 and 78 for lag or time of flight are attached. To the upper end of the lever 108 there is attached a connecting rod 109 which at its inner end is pivoted to a time-of-flight slide 110. This slide has the same range of movement as the elevation slide and traverses only the width of the film.

The slides 101, 102, 106 and 110 enter a housing or cabinet 112 of the editor or camera 80, as shown in Figure 13. Inside the housing (see Figure 14) the slides 101, 102, 106 and 110 carry lenses 115, 116, 117 and 118 which traverse the space behind the sensitized control band 30 which moves down in gate mechanism 121 as required by the claw type intermittent pull-down mechanism 122. A rotary shutter 123 carried on a shaft 124 is synchronized with the pull-down mechanism. At a fixed location adjacent the film position at the gate mechanism there is mounted a lens 125 in the line of a light tube 126 provided with a slit for forming the horizontal index line 37 (Figure 1).

The lens 118 is not mounted directly on the slide 110 but at the lower end of a light tube 127 which is carried by the slide 110 and upon rollers 128 operating upon a track 129 which is parallel to the slide tracks 130.

The lenses 115, 116 and 117 for the HR slide

101, the HL slide 102, and the V slide 106, respectively, are placed at the front end of light tubes 133, 134 and 135, respectively, which are secured to the slides. These tubes enlarge in both directions horizontally and in both directions vertically and at their enlarged rear ends are connected to slide frames 136, 137 and 138, respectively.

In addition to their support on the slides at 10 the front end through the light tubes, the slide frames at their rear ends are provided with rollers 139, 140 and 141 which ride on tracks 142, 143 and 144, respectively. The slide frames, including 15 their light tubes are rather long and might cause the slides to bind, so the rear ends are geared to be driven evenly with the slides. For this purpose the slide frames at their rear ends are provided with racks 147, 148 and 149, respectively. Through shafts 151, 152 and 153 provided with 20 pinions on both ends, the racks 147, 148 and 149 are driven from rack gears provided on the slides 101, 102 and 106.

As best shown in Figure 15, each light tube 133, 134 and 135 is closed tightly at the rear end except for a center opening 155 behind which (Figures 16 and 17) is located a lamp chamber 156 carrying a lamp 157. Flexible leads 158 connected to the lamps are long enough to permit the necessary sliding movements of the slide 30 frames on which the lamps are mounted to prevent fouling or breakage of the leads.

On each slide frame 136, 137 and 138 there is mounted a turnable annular multi-facet mask band 160. It may be mounted on a disk 161 provided with a hub 162 which is rotatable on a vertical shaft 163 mounted on a slide frame. As shown, the mask band carries twelve masks provided with apertures of varying sizes to take account of varying target distances, all as explained 40 above in connection with the light apertures formed in the control band by the masks (Figures 8 and 9).

Inasmuch as the three apertures HR, HL and V together define a single aim spot, the three 45 mask bands must rotate together to represent any predetermined target distance; but inasmuch as the frames on which the mask bands are mounted slide separately in different relationships, there must be separate means for rotating each mask band in any traversed position which it may assume. Such means, as shown in 50 Figures 15, comprises a toothed pinion 165 fixed on a shaft 166 rotatably mounted in a bearing 167 carried by a slide frame. The teeth of the pinion 55 operate in an annular row of holes 168 formed in an annular element secured to the mask band. The outer end of a shaft 166 is slidably splined in a drive pinion 169. The several drive pinions 169 for the three slide frames operate between 60 fixed guides and are driven by three pinions fast on a vertical shaft 170 which through suitable reduction gearing is driven by a motor M4 mounted on top of the housing 112.

The motor is started manually and is stopped 65 by an automatic control with the mask bands in approximately accurate positions and the mask is then accurately positioned by a spring pressed roller detent 173 (Figure 15) which cooperates with notches 174 formed in the edge of a member 70 carried by the mask band. Dropping of the detent after the automatic control has selected the desired mask operates a switch 175 to stop the motor. The motor stops after all three switches 175 have been operated and after the 75 required number of mask facets has been turned.

The desired mask of the multi-facet band 160 may be selected from the supervisor's control panel 66 through a split-disk commutator 180 (Figure 14) mounted on a shaft 181 which is geared to the motor M4 and the drive of the rotary mask bands 160. In Figure 14 an indicator disk 182 is shown on the external end of the shaft 181, this disk in conjunction with a fixed reference mark furnishing an indication as to which mask is in operating position on the focal axis. The supervisor is able to check the selection by indicators on the supervisor's panel. The commutator operates over contact studs HV-1 to HV-12 arranged in an arcuate double row 182. When any selected one of the contacts HV-1 to HV-12 is energized, as by pressing a corresponding lock-down button on the supervisor's panel, the split-disk commutator turns until the gap 183 is located over the energized contact, whereupon the current to the motor is discontinued and the band 160 is halted with the desired mask in the focal axis. Reversing contacts 184, 185 prevent the passage of the gap off the ends of the rows of contacts.

The operation of the apparatus begins with the projection of a target image on the screen S. As stated, there may be a plurality of projectors 65, though for simplicity only one is shown. When the picture is shown by a bank of projectors the bands are all synchronized and the pictures shown as they were photographed. The photographer will have obtained various essential data on the target, the gun intended to be used, and the firing conditions. In the editing room, on the first run after the films have been put in good condition, it is desired that the distance of the target from the gunner be obtained for each frame in which the target is within shooting range. For this purpose the film is projected frame by frame and an operator measures the target, as with the calipers of Figure 11. He compares the true distance from known sizes and observed angularity and adds this to the other data to be used in preparing the control film.

When all data are collected the supervisor is furnished with a log for each frame of the film. The editing devices 80, of which there may be several, one for each dummy gun to be used on the trainer, are loaded with sensitized control film and brought to a synchronized zero position along with the picture band or bands. The counters 82, 83, 84 on the supervisor's control panel may read 0, 0, 0. The entire apparatus is housed in a dark room; and if the editors have to be opened the picture projectors are cut off.

The pictures, during editing, are projected one frame at a time and the control bands exposed to light beams through the slide lenses 115, 116, 117, 118 and 125 (Figure 14). The projector motor may be used to place the picture and control bands as much out of phase as time of projectile flight from gun to target may demand, or to bring them back into phase. Both of the film drive motors M1 and M2 are of the inching type which can be operated to move one frame at each energization. They may also be run at constant speed when that is necessary. The counters show whether the film bands are abreast or have the correct displacement.

Having the proper control band frames in the exposure position, the supervisor operates the mask selector motor M4 to bring the desired mask into the focal axis. This is done, as stated, by pushing a button corresponding to target distance, HV-1 to HV-12, whereupon the split-

disk commutator 180 brings around the desired masks. The turning bands 160 for the two horizontal zones and the one vertical zone are turned together.

Next the pointer (or pointers) 67 are trained upon the target on the screen S, which brings the slides 101, 106, 102 (the aim slides) into proper position, and along with them brings the mask slide frames 136, 137, 138 and their selected masks into proper position.

The time of flight slide 110, with its frame 127, is moved into proper position by turning the selector 16 as required by the computed time of flight. Incidentally, while the selector is shown apart for schematic representation it, like the other controls, may be mounted on the supervisor's control panel.

With all exposure lights in the editor turned on, for aim, time of flight, and for the horizontal registry line (also for the trajectory control when provided though it is not present here and may be embodied in other equipment for re-exposure), the camera motor is operated to operate the shutter 123 and expose the film frame portions which fall in the lighted zones. Electrical and mechanical interlocks are provided to prevent operation of the shutter if the masks and commutator are not stopped accurately in proper position. The detent switch 175 forms part of this interlock.

At this time or later the motors M1 and M2 are operated to move the picture and control bands forward by one frame. Similarly by adjusting the control film the indicia for a second target may be placed on the control band by a second exposure to reach the unexposed areas, as note Figure 1.

It is thus seen that the invention provides very convenient apparatus for photographically preparing or "editing" control band of the specified type. However, the principles of the invention in one aspect or another may have other uses.

While one embodiment of the invention has been illustrated and described by way of example, it is to be understood that there may be various embodiments within the limits of the prior art and the scope of the subjoined claims.

We claim as our invention:

1. In gunnery training apparatus, in combination, a projector for throwing a target image from a picture frame on a screen, a pointer in the nature of a dummy gun to be directed toward said target, an editing device for placing aim indicia on a control frame, said editing device including an exposure slide movable transversely across said control frame in response to horizontal movements of said pointer for indicating aim azimuth, and a second slide movable transversely across said control frame in response to vertical movements of said pointer for indicating aim elevation.

2. In gunnery training apparatus, in combination, a projector for throwing a target image from a picture frame on a screen, a pointer in the nature of a dummy gun to be directed toward said target, an editing device for placing aim indicia on a control frame, said editing device including two connected reversely moving exposure slides movable transversely across said control frame in response to horizontal movements of said pointer for indicating aim azimuth, and a third slide movable transversely across said control frame in response to vertical movements of said pointer for indicating aim elevation.

3. In gunnery training apparatus, in combination, a projector for throwing a target image from a picture frame on a screen, a pointer in the nature of a dummy gun to be directed toward said target, an editing device for placing aim indicia on a control frame, said editing device including two connected reversely moving exposure slides movable transversely across said control frame in response to horizontal movements of said pointer for indicating aim azimuth, and a third slide movable transversely across said control frame in response to vertical movements of said pointer for indicating aim elevation, said azimuth slides indicating from an edge index line on the control frame azimuth distances from each side of a vertical line on the screen, and said elevation slide indicating from the same edge index line on the control frame elevation distances down from a top horizontal line on the screen.

4. In gunnery training apparatus, in combination, a sensitized control frame on which indicia are to be placed, an aperture slide movable across said frame, a light supply means mounted to move with said slide, and a plurality of masks of different light transmission value mounted to move with said light supply means and slide and selectively positionable relative to said light supply means for selectively producing indicia of different light transmission value on the frame in any traversed position of the slides.

5. In gunnery training apparatus, in combination, a sensitized control frame on which indicia are to be placed, an aperture slide movable across said frame, a light supply means mounted to move with said slide, means mounted to move with said slide and carrying a plurality of masks of different light transmitting values for selective disposal relative to said frame and said light source means, and means for selectively positioning said masks in any traversed position of said slide, light source means, and mask carrying means.

6. In gunnery training apparatus, in combination, a sensitized control frame on which indicia are to be placed, a plurality of aperture slides movable across said frame, a lamp mounted on each of a plurality of slides, a rotatable mask carrier having a plurality of different indicia masks of different light transmitting values mounted on said slides, and means for moving all of said mask carriers together for selectively positioning different masks in any position of the slides.

7. In gunnery training apparatus, in combination, a sensitized control frame on which indicia are to be placed, a plurality of aperture slides separately movable across said frame, a lamp mounted on each slide, a rotatable carrier mounted on each of a plurality of slides and having a plurality of masks with apertures of different size, and means for rotating said carriers in any position of a slide for selectively positioning different masks in association with a lamp and the frame.

8. In gunnery training apparatus, in combination, a sensitized control band, means for moving said band frame by frame to an exposure position, and means for placing indicia at selective transverse locations in a plurality of parallel transverse zones on a frame of said band, said indicia placing means comprising a plurality of parallel slides each carrying a lamp and an indicia-forming aperture mask.

9. In gunnery training apparatus, in combination, a sensitized control band, means for moving

5 said band frame by frame to an exposure position, and means for placing indicia at selective transverse locations in a plurality of parallel transverse zones on a frame of said band, said indicia placing means comprising a plurality of parallel slides each carrying a lamp and a plurality of selective indicia-forming aperture masks.

10. In gunnery training apparatus, in combination, a sensitized control band, means for moving said band frame by frame to an exposure position, means including transversely movable slides and light means for photographically placing indicia apertures at selective transverse locations in a plurality of parallel transverse zones on a frame of said band, and means for placing a transverse registration aperture line across said band parallel to said zones.

11. In gunnery training apparatus, in combination, a sensitized control band, means for moving said band frame by frame to an exposure position, 20 means including transversely movable slides and light means for placing indicia at selective transverse locations in a plurality of spaced parallel transverse zones on a frame of said band, means for placing a transversely registration aperture line across said band parallel to said zones, and means for placing other indicia at a selective transverse location in a parallel transverse zone.

12. In gunnery training apparatus, in combination, an exposure opening, an exposure slide movable across said opening, a plurality of aperture masks of different light transmitting values carried on said slide, means for moving said slide across said aperture, means for moving a selected 35 one of said masks into operative position on said slide, and means for directing a light beam of different size and different position in said aperture in accordance with the mask which is in the projecting position and the transverse position of the slide.

13. In gunnery training apparatus, in combination, an exposure opening, an exposure slide movable across said opening, a plurality of aperture masks of different light transmitting values carried on said slide, means for moving said slide across said aperture, means for moving a selected one of said masks into operative position on said slide, and means for directing a light beam of different size and different position in said aperture in accordance with the mask which is in the projecting position and the transverse position of the slide, said mask moving means including actuating means at a fixed location and connections from the fixed actuating means to mask moving means on said slide.

14. In gunnery training apparatus, in combination, camera mechanism for moving and exposing a sensitized control band frame by frame, a plurality of aim registry devices movable across a frame of the control band, a mask carrier movably mounted on each movable aim registry device, means including a remote actuator for moving each of said aim registry devices a selected distance across said frame, and means including a remote selector for moving all of said mask carriers together to place a selected set of masks into operative position on said devices.

15. In gunnery training apparatus, in combination, camera mechanism for moving and exposing a sensitized control band frame by frame, a plurality of aim registry aperture slides movable across the frame exposure opening, a rotary aperture mask carrier mounted on each slide, means for moving said slides separately, and

means for moving said mask carriers together in any position of the carriers.

16. In gunnery training apparatus, in combination, a projector for throwing a target image from a picture frame on a screen, a pointer in the nature of a dummy gun to be directed toward said target and movable in elevation and train, a control frame, a plurality of apertured slides mounted for movement transversely in parallelism across said frame, and connecting means between said pointer and said slides for moving one of said slides transversely when the pointer moves in elevation and for moving another one of said slides transversely when the pointer moves in train.

17. In gunnery training apparatus, in combination, a projector for throwing a target image from a picture frame on a screen, a pointer mounted before the screen and movable in elevation and train to aim for an image on said screen, a control frame provided with three adjacent parallel transverse zones for indicia apertures of elevation and train, an apertured slide movable transversely across said zones, one for elevation and two for train, the slides for train being connected together for reverse movement and having apertures which are both aligned with a marginal index line of the control band when the slides for train are in central position, and connecting means between the pointer and slides for moving the elevation slide when the pointer moves in elevation and for moving said train slides in opposite directions when the pointer moves in train, the one train slide aper-

ture moving across its zone on the control frame when the pointer moves in one direction from a central position, and the other train slide aperture moving across its zone on the control frame when the pointer moves in the other direction from a central position.

FRED WALLER.

WILLIS ROBERT DRESSER.
